ANTENNA POSITION INDICATOR
Margaret V. Finken, 6928 Braddock Road,
Springfield, Va.
Filed Feb. 4, 1963, Ser. No. 256,042
7 Claims. (Cl. 116—114)

This invention relates to an antenna position indicator for use with radio or television receiving sets and more particularly to position indicators for pole-type antennas.

Pole antennas, both single pole and dipole or "rabbit ears" antennas, are widely used with radio and television receivers, many receivers having the antenna structure built into the cabinet. It is well known that the angular position and the direction of the pole affects the reception, and that for any given transmission frequency there is an optimum setting of the antenna pole. Setting of the antenna is effected by a trial and error method; and when the receiver is tuned to different transmission frequencies, the setting of the antenna must be changed by the trial and error method.

According to the present invention, I provide an indicator which indicates the optimum antenna position for each transmission frequency whereby the adjustment of the receiver antenna is facilitated; and the trial and error method is eliminated. The invention will be described in relation to television receivers, but it will be apparent to those skilled in the art that it is equally applicable to radio receivers. It will also be apparent that the indicator of my invention is useful both with receivers having built in pole antennas as well as receivers employing separate pole antenna units.

Accordingly, the principal object of my invention is to provide an indicator for pole-type antennas which is simple and inexpensive to construct and which readily indicates the optimum setting for each transmission channel or frequency.

Referring to the accompanying drawing, FIG. 1 is a view of a television receiver with the antenna position indicator of the invention positioned thereon. FIG. 2 is an enlarged view of a portion of the embodiment of the invention shown in FIG. 1.

FIG. 3 is a view of a portion of a second embodiment of the invention. FIG. 4 is a view taken along lines 4—4 of FIG. 3.

The indicator 20 comprises a base 10 made of metal, plastic, or other suitable material carrying a plurality of adjustable pole antenna-simulating units. The indicator 20 is preferably placed on the receiver 11 as shown in FIG. 1 but may also be placed adjacent it. Preferably, the base is secured to the receiver as by a pressure-sensitive adhesive, magnetically, or in other well-known manners so it is fixed with respect to the receiver.

The base carries suitable indicia 14 which are preferably changeable corresponding, for example, to the VHF channels for television stations receivable in the area, there being one antenna-simulating unit for each such channel. As shown in FIG. 2, each antenna-simulating unit in this embodiment comprises a body 12 of penetrable material. Suitable materials include sponge rubber, expanded resins such as foamed polystyrene, and the like. A pin 13, simulating a single pole of an antenna, is stuck into the body 12 at such direction and angle to indicate the optimum setting for the indicated channel. If the receiver utilizes a dipole antenna, two such pins 13 will be inserted in each body 12 to simulate a dipole antenna.

In use, the antenna-simulating units are first adjusted and set to the optimum setting for each respective channel in the following manner. With reference to FIG. 1, the receiver is turned on and tuned to channel 4, for example. The receiver antenna poles 19 are then adjusted as to

2

direction and angle to the optimum setting. Then the dummy antenna corresponding to channel 4 on the indicator is set to the same directional and angular relationship as the receiver antenna poles 19 by visual comparison. The same procedure is followed for each channel receivable in the area.

Once the indicator has been set to indicate the optimum setting for each channel, it is apparent that it requires no further adjustment so long as the receiver is not moved. When the receiver is in use, it is apparent that the adjustment and setting of the receiver antenna poles 19 to the optimum position is easily and quickly effected for any channel by manually positioning the poles 19 parallel to the antenna-simulating poles corresponding to the channel in question. This is accomplished by mere visual comparison of the indicator and the receiver antenna.

It will be apparent that the indicator of FIGS. 1 and 2 is equally utilizable with receiver antennas of both single pole and dipole types. Additionally, if the receiver antenna poles 19 require shortening by telescoping to effect best reception (most such pole antennas are of telescoping construction), the indicator can simulate this setting by utilizing pins 13 of different length and also by merely inserting the pins to different depths in the penetrable body 12.

Another embodiment of my invention is illustrated in FIGS. 3 and 4. In this embodiment, each antenna simulating unit comprises a pin 17 carrying a ball 16 mounted in a socket 18 on the base 10. The ball-and-socket arrangement permits limited universal movement, as shown in FIG. 4, to indicate the optimum setting of each pole-simulating pin 17. It is apparent that this embodiment is equally applicable to both single pole and dipole antenna construction. In addition, the pole-simulating pins 17 can be of telescoping construction (not shown) to indicate such a setting for optimum reception.

The indicator of my invention may be built into radio and television receivers as an integral part thereof or may be manufactured and sold as a separate unit as will be apparent to those skilled in the art. It will also be understood that the invention is applicable to loop-type antennas wherein a plurality of miniature loops are supported on a base for universal movement and adjustment. Loop antennas are frequently employed in television receivers for UHF channels.

While the invention has been described with reference to certain embodiments, they are to be considered illustrative rather than limiting; and it is intended to cover all further embodiments that fall within the spirit and scope of the appended claims.

I claim:

1. An antenna position indicator comprising a base, a plurality of antenna-simulating pole units mounted on said base, frequency indicia display means carried by said base for each of said antenna-simulating units, and means for adjusting and fixing the direction and angular position of each pole with respect to said base.
2. An indicator as set forth in claim 1 wherein each said pole unit comprises a pair of poles simulating a dipole antenna.
3. An antenna position indicator comprising a base, a plurality of penetrable bodies mounted on said base, each said body removably supporting a pin member simulating an antenna pole and frequency indicia display means carried by said base for each of said penetrable bodies.
4. An indicator as set forth in claim 3 wherein each said body removably supports a pair of pins simulating a dipole antenna.
5. An antenna position indicator comprising a base, a plurality of sockets mounted on said base, each said

socket adjustably carrying a ball member having secured thereto a pin simulating an antenna pole and frequency indicia display means carried by said base for each of said antenna simulating pins.

6. An indicator as set forth in claim 5 wherein said sockets are arranged in pairs whereby each pair of pins carried thereby simulates a dipole antenna and frequency indicia display means carried by said base for each of said pairs of pins.

7. An antenna position indicator comprising a base, a plurality of miniature antenna-simulating units mounted

on said base, frequency indicia display means carried by said base for each of said antenna-simulating units and means for adjusting and fixing the position and direction of each said antenna-simulating unit with respect to said base.
